Primary Examiner — Catherine A Tuttle(74) *Attorney, Agent, or Firm* — Not Just Patents LLC; Wendy S Peterson(57) **CLAIM**

The ornamental design for a human foosball playing field, as shown and described.

DESCRIPTION

FIG. 1 is a top, front, right perspective view of a human foosball playing field showing our new design;

FIG. 2 is a top view thereof;

FIG. 3 is a bottom view thereof;

FIG. 4 is a left view thereof;

FIG. 5 is a right view thereof;

FIG. 6 is a back view thereof; and,

FIG. 7 is a front view thereof.

The dashed lines in FIGS. 1, 6, and 7 depict features of the human foosball playing field that form no part of the claimed design.

1 Claim, 5 Drawing Sheets(56)
